UNITED STATES PATENT OFFICE.

DALE G. STEELY, OF CAMBRIDGE, FREDERICK W. BLAKE, OF MEDFORD HILLSIDE, AND GUSTAV A. LORENTZEN, OF WEST SOMERVILLE, MASSACHUSETTS.

EXTENSION-EDGE BOX-FORMING MACHINE.

1,332,641.

Specification of Letters Patent.

Patented Mar. 2, 1920.

Application filed May 26, 1917. Serial No. 171,255.

To all whom it may concern:

Be it known that we, DALE G. STEELY, FREDERICK W. BLAKE, and GUSTAV A. LORENTZEN, residing, respectively, at Cambridge, Medford Hillside, and West Somerville, all in the county of Middlesex and State of Massachusetts, have invented an Improvement in Extension-Edge Box-Forming Machines, of which the following is a specification.

This invention relates to an edge extension box forming machine, wherein an otherwise complete box form is provided, with an additional section to present an edge extension for the ornamental finish, known as an "extension-edge box."

The box which this machine is designed to handle, is either as a body or top, completed except as to covering and lining, on any ordinary box machine, and in such complete form delivered to the machine forming the subject matter of the present invention, and has applied thereto by the present machine, a section of greater dimensions than those of the box proper, whereby to present a projecting edge surface on the box or cover, or both, for ornamental purposes.

The present machine involves a revolving carrier with a series of box forms, on each of which there is to be successively placed an otherwise complete box. The carrier is given an intermittent movement, and during its periods of rest the box on a particular form is in alinement with a section feeder, constructed to automatically deliver to the box a section of material to form the projecting edge portion of the said box.

The section feeder receives the sections in superimposed relation or pile form, and the operative parts connected with said feeder, automatically apply paste to the lowermost section of the pile, force said section from the pile, deliver it onto the complete box, and in proper relation to the surface thereof, centering such section to form an evenly projected edge beyond the box. Immediately succeeding the placing of the section, as described, a press member operates to exert pressure on the section, to initially fix the same upon the box, the said box and section, in the next movement of

the carrier, being brought beneath a final press, for the application of sufficient pressure to the section to insure complete adherence thereof to the box.

55

The present machine, in the preferred form, is illustrated in the accompanying drawings, in which:—

Fig. 1 is a plan view of the machine.

Fig. 2 is a side elevation of the same.

Fig. 3 is a front elevation of the same.

Fig. 4 is a sectional detail, illustrating the means for intermittently rotating the carrier, and for locking the carrier, at points of rest.

65

Fig. 5 is a longitudinal section through the section feeder, and a portion of the carrier, showing the position of the parts immediately succeeding the application of an extension section to the box, and the release of the mutual pressure thereon.

Fig. 6 is a transverse sectional view through the extension section feeder.

Fig. 7 is a detail and elevation, illustrating the means for positively operating the final press in both directions.

Fig. 8 is a plan showing a modified means for operating the carrier.

Fig. 9 is a plan detail showing the followers for delivering the extension-edge sections.

80

The machine of the present invention is here shown as comprising a main frame including a bed-plate 1, having legs 2. In the rear portion of the bed-plate, mounted in suitable bearings, secured to or carried on said plate, is a shaft 3, on the upper end of which above the bed-plate is fixed, in any desired appropriate manner, a carrier 4.

The carrier is preferably of wheel-like structure, having a hub portion secured upon the shaft, and a series of radiating spokes supporting a rim 5, at their outer ends. Secured upon the rim are what may be termed tables 6, that is, imperforate metallic block-like members, having a square upper surface, and in all lineal dimensions corresponding to the interior dimensions of the box or cover to which the extension edge section is to be applied. The tables 6 are or may be removably secured to the rim 5, in order that tables of various sizes may be substituted, to accommodate the machine for

coöperation with boxes of different sizes. A series of such tables 6 are arranged on a rim, six such tables being here shown. The tables are arranged with their major dimensions tangentially of the rim, and the width of the rim is preferably materially less than the similar dimension of the table.

For the purposes of the machine, it is important that the carrier be given an intermittent revolving motion, having periods of rest during which the various operations of the machine, with respect to the extension edge forming section, are carried out. It is, therefore, important that the movement of the carrier be more or less accurately timed, and that the respective periods of rest be absolutely uniform and regular, in order that each table with its carried boxes or top may be successively operated upon by the various mechanisms to be described.

Movement and control of the carrier is had primarily through an operating shaft 7, supported in bearings in the main frame below the bed-plate 1. The operating shaft 25 is driven through the gearing connection 8, with a drive shaft 9, also mounted in bearings in the main frame, and in turn geared at 10, to a power shaft 11, mounted in main frame bearings, and having a belt wheel 12 to be turned by a belt 13, driven from any power source, in this instance, a motor 14.

Secured upon the shaft 3 is a disk 15, formed in the peripheral edge thereof, with a series of notches 16, the notches corresponding in number to the number of tables in the carrier. Mounted for independent rotary movement upon shaft 3, is an arm 17, the free end of which is connected, through appropriate connections, with one end of the rod 18, the opposite end of which is connected to the crank 19, arranged upon the relatively inner end of the operating shaft 7, so that in the operation of the shaft, a rotary reciprocatory movement is imparted to the arm.

For this purpose, there is secured on the under side of the bed-plate, a block 21, in which is slidably mounted a spring pressed locking dog 22, operative, when under the free influence of its spring, to engage a notch in said disk 15, and lock the disk, and thereby the table, for the operation of the mechanism for applying and fixing the extension edge section. Pivoted to the shaft 3, below the disk 15, is an arm 23, the free end of which is connected through rod 24 and lever 25, with a cam disk 26, secured upon the shaft 7. The lever 25 is pivoted at 25' to the table, and extends downwardly, the rod 24, being connected to the lower end, as at 24', and said lever is provided with a pin or roller 27 to engage the groove of the cam 26. The arm 23 is extended beyond the shaft 3, as a release section 28, the outer or free edge of which is so arranged as to en-

gage a projecting portion 29, or to be engaged by a projecting portion 30, of the respective dogs 22 and 20.

The cam 26 is so timed that, immediately following an operative movement of the carrier through the actuation of the arm 17, when locked to the disk, the projection 30 of the dog 20, will engage the free end of the release section 28, to force said dog from engagement with a particular notch 16, 75 thus freeing the arm from the disk, and permitting the crank to return the arm to an operative position, for a succeeding action, the angularity of the sides of the release section 28, and the dogs, during the releasing operation, being sufficient to accomplish the result.

The locking dog 22 will, of course, engage the particular notch 16, alined therewith, as the carrier stops, and following the operation of the placing mechanism, the cam 26 swings the arm 23 in a direction and to an extent to cause the release section 28 to engage the projection 29 of the locking dog 22, and force the dog to a release position, 80 to free the carrier for further movement.

The feeder for the extension edge section is mounted on the frame and disposed so that in the rest periods of the carrier a table will be directly alined therewith radially of 95 the table. The feeder comprises uprights 31 rising from the frame, in which is adjustably mounted the bin 32 for receiving the extension edge sections in superimposed relation, or in pile form. The bin 32 comprises side strips 33 of appropriate height, having inward extensions 34 at their rear or inner edges to position the rear corners of the extension-edge section, and forwardly extending guide arms 35 at their lower edge. 100

A follower is mounted for sliding movement in the bin frame to force the lowermost extension-edge section onto the box on the table, the follower comprising bars 36 slidably mounted in the guide arms 35, the bars 110 and arms being of appropriate sectional formation to permit such movement without separation. The follower bars have their relatively forward portions, or those portions normally underlying the edge-section 115 in the bin, of slight width, being, in fact, just of sufficient size to support the section, while the forward portion of the bars are of greater width, as at 37, and an increased height over the reduced width portion equal 120 to the thickness of an extension edge section. The junctions of the respective sections of the follower bars present abrupt shoulders 37' to engage and push the lowermost section from the pile, the broader portions of 125 the bars supporting the pile meanwhile.

The bin includes the adjustable forward walls 38, which may be readily moved to accommodate extension-edge sections of different widths, such wall being supported on 130

- rods 39, slidably mounted in bearings 40, and fixed in adjusted positions by set screws 41. The bearings are in turn arranged on rods 42, preferably two, the ends of which 5 pass loosely through openings in the guide arms, or extensions 44 thereof. The bin as a whole is adjustable to accommodate extension-edge sections of different lengths, through reversely threaded connections on 10 shafts 45 and 46, passing respectively through extensions of the side walls and extensions of the guide arms. The shafts are connected for similar and simultaneous movement, as by chain and sprocket 47, and 15 are adapted for manual operation, as the shaft 45 is provided with a hand wheel 48. Adjustment of the bin parts to accommodate extension-edge sections of different sizes is thus obviously provided for. A bearing block 49 is arranged at the rear portion 20 of the bin, supported by the shaft 45 and other shafts to be mentioned, and slidably connected to the block, by a dovetailed connection, is a narrow strip 50, adjustable vertically through adjusting screw 51, such strip forming the rear wall of the bin, and serving to prevent rearward movement of other than the lowermost extension edge 25 section from the bin.
- 20 A paste receptacle 52 is supported on the uprights 31 and directly below the bin. A paster 53 is mounted for vertical movement in the receptacle and to a position to apply paste to the lowermost extension edge section of the pile. The paster is in the form of an open rectangular frame having depending side portions connected by pins 55 with rods 56, slidably mounted in guides 57 projecting from the side walls of the bin. The 30 pins 55 are slidable on their bearings to permit movement in adjustment of the bin width as previously described. The paster is preferably of the form shown to apply paste only in a rectangular line to the bottom of the extension edge section, as this has been found sufficient for the purpose. However, the use of a paster of any form is contemplated.
- 30 The follower is reciprocated for feeding purposes, through a throw frame 58, including a shaft 59, on which is slidably mounted link 60, connected to the respective follower bars, the connection between the shaft 59 and links 60 permitting necessary movement 35 in the size adjustment of the bin. The above frame is pivoted at 58' to the main frame, or extension thereof, and is operated through a rod 61, connected at its rear end to a lever 62, pivoted to the main frame, and having a 40 roller 63, seating in a cam groove 64 of a cam 65, mounted on shaft 7.
- 40 The outer end of rod 61 has an adjustable connection with the arm or arms of the throw frame, including a pivotally mounted block 66, having an open jaw 67 to receive 45
- the arm of the throw frame. One position of the jaw carries a spring 68 to bear on the throw frame arm, and the other portion has a set screw 69 to permit adjustment of the throw frame movement, in order that the 50 followers may be moved with the necessary accuracy to exactly position the extension edge section on the box or cover. The paster is also timed and operated, through a shaft 70, mounted in the uprights 31 and also 55 opening through the bearing block 49. This shaft 70 is connected by links with the rods 56, and is rotatably reciprocated to operate the paster, through an end link or arm 71 secured to the shaft and to the upper end of a 60 rod 72, secured at its lower end to one end of lever 73, the opposite end of which is connected to the main frame. The lever 73 carries a roller 74 operative in a cam groove 75 of a cam wheel 76 secured on shaft 7. 65
- 65 The feeder thus, in properly timed sequence, pastes the lowermost extension-edge section of the pile in the bin, carries such pasted section from beneath the pile, and deposits it upon the exposed surface of the 70 box or cover upon the particular table held in alignment with the feeder, through the described intermittent movement of the carrier.
- 70 Following the application of the extension-edge section to the box or cover, an initial press operates to fix the section in place on the box or cover. This press, in the form of a plate 77, substantially equal to the surface area of the box or cover, is spring supported on rods 78, which pass through arms 79, pivotally mounted on the uprights 31, and connected, for vertically reciprocating the press, to a rod 80, connected in turn to a lever 81, pivotally supported at one end to 100 the frame, and having a roller 82, operating in a cam groove 83, in a cam-wheel 84 secured on shaft 7. The press is thus turned to force the extension-edge section in place on the box or cover, after the same has been 105 carried thereto by the follower.
- 75 The press 77 is preferably provided with an adjustable edge guide 85, depending from the inner edge thereof, and which in the maximum upper position of the press does 110 not rise above the surface of the box or cover. This guide limits the innermost position of the extension-edge section when being delivered by the follower, and through its adjustment may be utilized to accurately 115 position the section to provide an equal edge projection thereof beyond the box or cover. The press 77 also carries a spring-finger 86 (Fig. 1), so positioned that its free terminal rides over the box or cover on the 120 table being advanced to the feeder, with the effect to properly seat such box or cover on the table.
- 80 A final press is employed to apply a heavy affixing pressure to the extension-edge sec- 130

tion and box, and this press is preferably positioned to act upon the same at the period of rest immediately succeeding the feeding operation, that is, the next step. The final 5 press comprises a comparatively heavy plate 87, carried by a standard 88 slidably mounted in a bearing 89 rising above and extending below the bed-plate 1, the standard having a foot 90. An operating toggle 91 is 10 connected to the bed-plate and to a rod 92, passing through the foot and provided below the same with nut 93. The rod 92 has a collar 94 thereon, and on the rod between the collar and the bottom of a recess 95 formed 15 in the foot about the rod, is arranged a stiff coil spring 96. The toggle is operated in both directions through a yoke 97, connected to the joint of the toggle by a link 98, and having opposed cam rollers 99, 100, engaging 20 respectively cams 101, 102, on shaft 7. The final press is designed to exert the final pressure during practically the entire period of rest of the particular table, following which, at a succeeding period of rest, the 25 box or cover, with the extension-edge section applied thereto, may be removed from the table by hand.

It sometimes occurs, in the operation of the machine, that the box, or cover, adheres 30 to the press when the latter is raised at the end of the pressing operation. In order to secure the detachment of the box, or cover, from the press in this event, stripping pins 103 are provided. These pins, two being 35 shown, are stationarily supported on arms 104, attached to the frame of the machine, and extend through the press plate 87 and said press plate is adapted to reciprocate about said stationary pins.

40 When the press plate 87 is at the lowest part of its stroke and in engagement with the box, or cover, the length of the pins 103 is such that the ends thereof are above the face of the said plate 87, and are, therefore, 45 not in engagement with the box. When, however, the press plate returns to its initial position, the face of said plate is raised above the ends of said pins, and an adhering box or cover is brought in contact with said 50 pins. As the pins are stationary and therefore hold the box against further upward movement, the continued upward movement of the press plate causes the detachment of the box or cover, and the box falls to the 55 table beneath, from which it may be removed.

The machine, fed by hand or otherwise, receives a box or cover on each table, and applies and affixes an extension-edge section 60 thereto, the positioning of the extension-edge

section on the box or cover positively and accurately constituting one of the essential features of the invention.

We claim:—

1. A machine of the class described, comprising an intermittently rotating carrier having a plurality of tables for boxes and the like, said carrier having a component thereof slotted to correspond with the plurality of tables, a dog engageable with the slotted component to move the table, a second dog engageable with the slotted component to restrain said table in its moved position, and means alternately engageable with said dogs to release them from locking engagement with said carrier. 65 70 75

2. A machine of the class described, comprising a horizontal rotatable carrier, a plurality of horizontally arranged tables mounted on the periphery thereof and equidistant from each other, a blank-holding magazine located at one side of said carrier and in operative relation thereto, a reciprocating feeding device beneath said magazine for feeding blanks therefrom, means for rotating said carrier step-by-step to bring said plurality of tables successively into alignment with the path of movement of said feeding device, a pasting device located below said magazine, and vertically movable with respect thereto, for applying adhesive to the lower face of the blanks in the magazine, and means for operating said device prior to each reciprocation of the feeding 80 85 90 95 device. 100

3. A machine of the class described, comprising a press, a plurality of work holding tables movable successively into position beneath said press, a blank-holding magazine, a reciprocating feeding device located beneath the magazine and adapted to force the lowermost blank in the magazine out therefrom and into position between the press and each of the tables successively, a pasting device located beneath the magazine and adapted to apply adhesive to the bottom face of each blank in succession, and means for operating said mechanisms to first apply adhesive to the blank, feed the blank and position it on the table, and then force the blank into engagement with the work on the table. 105 110 115
